UNITED STATES PATENT OFFICE.

MALCOLM M. COPPUCK, OF PHILADELPHIA, PENNSYLVANIA, ASSIGNOR TO CHARLES NOBLE AND COMPANY, OF SAME PLACE.

DESIGN FOR A COOKING-STOVE.

Specification forming part of Design No. **6,618**, dated April 29, 1873; application filed April 8, 1873.

To all whom it may concern:

Be it known that I, MALCOLM M. COPPUCK, of Philadelphia, Pennsylvania, have invented a Design for the Plates of the "Iron King" Cook-Stove, of which the following is a specification:

The nature of my invention is fully illustrated by the accompanying drawing, in which—

Figure 1 represents a view of the side plate and doors; Fig. 2, a view of the front plate with one of the doors; and Fig. 3, a view of one of the feet.

The side plate A has a molding, *a*, extending around it, and each of the doors B, C, and D, has a heavy edging or molding, *b*, within which are the connected corner ornaments *d*; and in the center of each door is a projecting ornament, *e*, of the character represented. Above the oven-door are the words "Iron King," and beneath the same and the door G

an oblong tablet, *f*. The front plate F has an edging, *h*, and oblong ornaments *i*, at either side of the doors G, the ornamentation of the latter being similar to that of the doors on the side plate.

The ornamentation of the foot H is of a character too clearly shown in the drawing to need description.

I claim—

The design for the plates of the iron-king cook-stove, substantially as described, and as represented in and by the accompanying drawing.

In testimony whereof I have signed my name to this specification in the presence of two subscribing witnesses.

M. M. COPPUCK.

Witnesses:

J. PLANKINTON,
JOHN LINERD.
